UNITED STATES PATENT OFFICE.

GUY W. FERDON, OF CRESSKILL, NEW JERSEY.

CLOTHES-POUNDER.

1,267,649.

Specification of Letters Patent. Patented May 28, 1918.

Application filed October 16, 1917. Serial No. 196,865.

To all whom it may concern:

Be it known that I, GUY W. FERDON, a citizen of the United States, residing at Cresskill, in the county of Bergen and State 5 of New Jersey, have invented certain new and useful Improvements in Clothes-Pounders, of which the following is a specification, reference being had therein to the accompanying drawing.

10 My invention relates to washers, particularly to washing devices of the clothes pounder type in which, by the reciprocation or pounding motion of a suitable device, water and a detergent and air are forced 15 through the interstices of soiled fabrics in a tub or other receptacle. My invention relates to certain novelties of structure in such devices, and I have produced a compact collapsible device easily taken apart and stored 20 or carried for use during traveling or under other conditions where space is restricted. I make the handle tubular and sectional with one or more joints. I make the washer of truncated cone-shape. I provide means 25 whereby air may be forced from the plunger through the water on the downward stroke. There are other improvements.

In the drawings,—

30 Figure 1 is a perspective exterior view; Fig. 2 is a view partly in section; and Fig. 3 is an enlarged view of a detail of the end of my inner tube.

In the drawings the numeral 1 represents the body of my washer made in the form of 35 a frustum here, of a cone through the top 2 of which is passed the handle 3, tubular in cross section and in two parts connected by any suitable joint, as the screw joint at 4. The upper part 5 is also hollow, with a 40 closed end 6 provided with an opening 7 of a size adapted to be covered by the ball of a thumb. A loop 8 for hanging the device up is provided. The part 3 is also provided with an opening adapted to be closed 45 in the same way as the opening 7 in case it is desired not to use the second or extension part 5 of the handle.

The tubular handle passes through the top 2 down toward the bottom of the main part 50 1 and is supported and stayed at its lower end by the tubes or rods 10 extending across the washer and through the tubular handle. These supports as here shown are two in number and cross each other within the 55 handle at right angles at 11. At the lower end of the tubular handle I place a pair of

rods or tubes 12, also two in number, crossing or intersecting at right angles. Obviously the number and direction of both of these may be changed. These parts 10 and 60 12 thus form a cage, and in this cage I have a disk or short cylinder 13 constituting a valve nearly as large as the tube. The two sets of rods are far enough apart to afford considerable play to the disk or short cylinder 13, and guided by the passage of water or air this valve will find itself at the lower or upper part of the cage to choke the passage. It is made of such a diameter or shape 65 that it will not close the passage entirely, but should be large enough to slow down the passing fluid. At some point or zone of the truncated cone shaped body, I provide one or more openings 14, and I may put around each of these holes a whistle 15, which will 70 give a whistling sound on the passage of air therethrough but will be silent when water passes and thus will serve to indicate depth of water in the washing receptacle and extent of submergence of the washer. The 75 frustum shape gives strength to the structure and needed space in the upper part of the washer.

In operation if the tub stands on the floor the complete handle is preferably used and 80 the washer reciprocated with an up and down motion. Each time it is pushed downward the operator should close the hole 7 with the ball of her thumb, at least when the level of openings 14 is reached in sub- 85 mergence. This will cause entrapped air to pass through the clothes in the water, 90 fully removing the dirt. On the upstroke the thumb may be removed if desired. When a wash basin or pail is used standing on a table, the part 5 is not necessary. Otherwise the action is the same. The valve 95 13 on the up-draw tends to move toward the bottom of its cage and to direct any air entering the tube out through the water. On the down-thrust it rests against the upper member of its cage and air and water are made to enter the side openings. The 100 valve is purposely a loose one so that this action is only in part, the lower part of the handle also serving to disturb the water and clothes. The effect is a gushing of jets through the side holes of the cup. By making my washer of the shape shown I secure the presence within it of a large body of 105 water while the sloping walls help to prevent the lodging of clothes or small articles,

like ladies' handkerchiefs, within the fountain.

The wires 10 below the holes 14 serve to keep the clothes from massing in the washer body. The wires 12 also serve to keep the clothes, particularly small articles, out of the tubular handle.

My device may be of any suitable shape and contour.

Having thus described my invention, what I claim as new, and desire to secure by Letters Patent, is:—

1. In a clothes pounder in combination an open mouthed washer body, a tubular handle entering the top of the washer body and extending below said top, stays secured to the inside of said washer body and crossing in and secured to said tubular handle, a pair of rods crossing in the lower part of the handle and secured thereto, the two pairs of crossing rods forming with the handle a cage and a valve within said cage adapted to move up and down therein.

2. In a clothes pounding device, in combination, a hollow open mouthed washer

body in the shape of a frustum, a tubular handle for said washer body, said handle passing through the top of the frustum and secured to discharge well within the washer body, braces passing through the handle for securing it, a cage in the lower end of the handle, and a valve within the cage to control passage of air and fluid through the handle, a side of said cage being formed by said securing braces.

3. In a clothes pounder, in combination, a hollow open mouthed frustum shaped washer body, a tubular open-ended handle for said body, said handle entering and terminating within the body, the upper end adapted to be closed by a thumb, a valve in the lower end for controlling passage of air, and an opening in said washer body near the upper end thereof through which jets of water may be made to squirt at will by control of the opening in the upper end of the handle as the device is reciprocated in use.

In testimony whereof, I affix my signature.

GUY W. FERDON.
